UNITED STATES PATENT OFFICE

147,541

DESIGN FOR A PITCHER

Rolf John Falk, Zanesville, Ohio, assignor to
Shawnee Pottery Company, Zanesville, Ohio, a
corporation of Ohio

Application April 20, 1946, Serial No. 128,807

Term of patent 14 years

(Cl. D44—21)

To all whom it may concern:

Be it known that I, Rolf J. Falk, a citizen of the United States of America, residing at Zanesville, in the county of Muskingum and State of Ohio, have invented a new, original, and ornamental Design for a Pitcher, of which the following is a specification, reference being had to the accompanying drawings, forming a part thereof, wherein:

Fig. 1 is a side elevation of a pitcher illustrating my new design; and

Fig. 2 is a perspective view thereof.

I claim:

The ornamental design for a pitcher, as shown.
ROLF JOHN FALK.
